(57) **CLAIM**

The ornamental design for the bond pattern for a substrate, as shown and described above.

DESCRIPTION

FIG. 1 is a perspective view of a bond pattern for a substrate; FIG. 2 is a view of the front side of the bond pattern for a substrate of FIG. 1; FIG. 3 is a view of the right side of the bond pattern for a substrate of FIG. 1; FIG. 4 is a view of the back side of the bond pattern for a substrate of FIG. 1; FIG. 5 is a view of the left side of the bond pattern for a substrate of FIG. 1; FIG. 6 is a view of the top side of the bond pattern for a substrate of FIG. 1; and, FIG. 7 is a view of the bottom side of the bond pattern for a substrate of FIG. 1. The broken lines are included for the purpose of illustrating environment and form no part of the claimed design.

1 Claim, 4 Drawing Sheets

Related U.S. Application Data

continuation of application No. 16/357,685, filed on Mar. 19, 2019, now Pat. No. 11,642,255.
